LAWN MOWER

Charles W. Butler, New York, N. Y., assignor to Toro Manufacturing Corporation, Minneapolis, Minn., a corporation of Minnesota

Application February 28, 1956, Serial No. 40,392

Term of patent 14 years

(Cl. D40—1)

Fig. 1 is a perspective view of a lawn mower showing my new design.

Fig. 2 is a plan view of the same.

Fig. 3 is a side elevational view taken from the right hand side as viewed from the rear.

Fig. 4 is a side elevational view taken from the left hand side as viewed from the rear.

Fig. 5 is a front end elevational view.

Fig. 6 is a rear end elevational view.

The characteristic features of the design reside in the full line portions.

I claim:

The ornamental design for a lawn mower, as shown and
